VENETIAN BLIND

Fred E. Lawson, Philadelphia, Pa.

Original application January 27, 1938, Serial No. 187,114. Divided and this application June 11, 1940, Serial No. 339,946

8 Claims. (Cl. 156—17)

The present invention relates to Venetian blinds, and particularly to the means for raising, lowering, and tilting of the slats of the blind disclosed in the copending application, Serial No. 187,114 filed January 27, 1938, which issued as United States Letters Patent No. 2,209,276, dated July 23, 1940, of which the present application is a division.

One object of the present invention is to provide improved means for removably supporting 10 the tilt bar in operative position.

Another object is to provide an improved ladder tape hanger bracket embodying a novel arrangement for supporting the bracket on the tilt bar and for connecting the ladder tape thereto.

Other objects and advantages of the present invention will more fully appear from the following detailed description taken in connection with the accompanying drawings, which illustrate a preferred embodiment thereof, as well as several variations in construction of detailed parts, and in which:

Fig. 1 is an elevational view of a Venetian blind embodying the features of the present invention;

Fig. 2 is an enlarged vertical fragmentary sectional view taken through the same substantially on line 2—2, Fig. 1;

Fig. 3 is an enlarged fragmentary sectional view, certain of the parts being disclosed in full lines, taken substantially on line 3—3, Fig. 2;

Fig. 4 is an enlarged fragmentary view having cut away portions disclosing certain details of construction, and showing the cooperative relationship of the means for raising and lowering the blind, and means for tilting the slats;

Fig. 5 is an enlarged fragmentary view having cut away portions in section, illustrating the construction of the tilt bar and brackets thereon for connection to the ladder tapes;

Fig. 6 is a transverse section of the same, taken substantially on line 6—6, Fig. 5;

Fig. 7 is an enlarged fragmentary view, partly in section, illustrating the details of a modified arrangement for permitting removal of the tilt bar from its pivotal supports;

Fig. 8 is a plan view of a modified construction of ladder tape supporting bracket mounted on the tilt bar; and

Fig. 9 is a sectional view of the same, taken substantially on line 9—9, Fig. 8.

Referring to Fig. 1, the blind is disclosed as being applied to a window frame, generally indicated at 15. It will be understood that this frame is provided with the usual sash, and that

this has been omitted for convenience of illustration.

Vertically disposed at the sides of the window frame are guide members which are in the form of V shaped channels 16 and 17. These channels are mounted substantially vertical and have their channel openings facing each other. The guide channels 16 and 17 are each supported by a bottom bracket 20 and top bracket 21.

The bracket 21 at the top end of each guide channel is substantially U-shaped. One leg 27 of the bracket is secured as by a screw 26 to the side of the window frame 15. The other leg 28 of the U-shaped bracket is disposed inwardly of the guide channel and is utilized as a pivotal support for a tilt bar 29, as will hereinafter be more fully described. The base portion of the bracket, this portion being disposed uppermost, serves as a mounting for a suitable pulley or pulleys 30 which serve as guide sheaves for the cable connection to the actuating mechanism.

The tilt bar 29 is of tubular construction, see Fig. 6, and is pivotally mounted for swinging movement on the innermost legs 28, 28 of the 25 top U-shaped brackets 21, 21 respectively. This bar, at its right end, see Fig. 5, is provided with a telescopically associated extension 31 which is axially adjustable in the tubular member 29, so that the bar may be adjustably lengthened or shortened. The member 31 is held in adjusted 30 position by a collar 32 arranged to fit over this end of the bar, this collar having a set screw 33 arranged to threadedly engage the bar and abut at its inner end against the member 31.

The other end of the bar 29 has affixed thereto a frusto-conical head 34 adapted to be disposed in correspondingly tapered socket 35 formed in a socket member 36 rotatably mounted in the innermost leg 28 of the U-shaped bracket 21 associated with the left guide channel 16, as shown in Figs. 3 and 4.

With the arrangement just described, it will be apparent that the tilt bar 29 may be easily removed simply by loosening the screw 33, whereupon the member 31 may be retracted from a normal supporting position with its outermost end disposed in a suitable opening 22 in the right hand top bracket 21. As soon as the bar 29 is shortened, by retracting the member 31, the bar may be shifted to the right so as to withdraw the tapered head 34 from its associated socket 35 in the member 36, thereby enabling the tilt bar to be readily removed.

The rotary socket member 36 is provided with 55 a diametrically reduced end portion 37 which de-

fines a shoulder 38. The shoulder 38 abuts the innermost surface of the inner leg 28 of the left hand bracket 21, when the contracted portion 37 is disposed in a suitable opening 39 in the associated bracket plate 28. Secured to the end of the contracted portion 37 is a gear 40, which is spaced from the associated bracket leg 28 by a spacer member 41.

Swingably mounted on the supporting leg 28 of the bracket 21 is a lever 42, a suitable pivot 43 being arranged between the ends of the lever. One end of the lever 42 is provided with a segmental gear 44 which meshes with the gear 40. The other end of the lever 42 has an actuating rod 45 connected thereto so as to hang downwardly in front of the blind arrangement and provide means whereby an operator may manually swing the lever 42 about its pivot point to cause rotative movements of the tilt bar 29.

In order that the bar 29 may be retained in angularly adjusted position, the socket member 36 has secured thereto, as by a key 46, a collar 47, see Fig. 2. The collar 47 carries a radially extending arm 48 which is provided at its outermost end with a housing 49 adapted to contain a ball 50, see Fig. 4, which is normally actuated by means of a spring 51 towards the supporting leg 28 of the associated bracket 21.

The leg 28 of the bracket 21, as shown, is in the form of a plate and is provided with a plurality of depressions 53 which are spaced apart in the arc of travel of the ball 50, so that as the ball moves over the plate it may be temporarily entered in the respective depressions, corresponding to the adjusted positions of the tilt bar.

Although a gear connection is disclosed between the lever 42 and the tilt bar, in this instance the gears having a ratio of substantially two to one, it will be apparent that the lever could be attached at one end directly to the tilt bar.

A pair of brackets, generally indicated at 54, are carried by the tilt bar 29. These brackets are respectively connected to ladder tapes 55 of usual construction arranged to support a plurality of slats 56 in the usual manner.

As more clearly shown in Figs. 5 and 6, each of these brackets comprises a pair of arms 57 and 58 which are respectively apertured intermediate their ends as shown at 59 to receive the bar 29 therethrough. The arm 58 is secured tightly to the bar 29 in any suitable manner, whereas the arm 57 is supported for sliding movement on the bar 29.

Each end of the arm 58 carries a pin 60 which extends at right angles to the arm and has one end fixedly secured thereto. The arm 57 is apertured as shown at 61 to receive the free end of the pin 60, this end of the pin 60 being provided with a circumferential groove 62 which is adapted to receive a spring 63 therein for latching the pin against removal from the arm 57.

The uppermost ends of the ladder tapes 55, 55 are respectively secured to the pins 60 lying on opposite sides of the bar 29 by means of metal ears or clips 64 which are secured to the ladder tape as by rivets 65 and define tubular portions at the end of the ladder tape adapted to receive the pin 60 therethrough and form a pivotal connection to the tape. With this arrangement, it is a very easy matter to disconnect the ladder tapes from their supporting brackets, this being accomplished simply by releasing the ends of the pins 60 which are engaged by the springs 63, whereupon the arms 57 and 58 may relatively be

5 moved away from each other to free the ends of the pins and permit the ears 64 to be axially removed from the pins.

Although I have shown a particular manner 10 of latching the ends of the pins 60 relative to the arms 57, it will be appreciated that other types of latches or other means may be utilized for this purpose, without departing from the scope and spirit of the invention.

15 It will be observed that the center lines of the pins 60 and the center line of the bar 29 lie in the same plane. This arrangement enables maximum tilting of the slats and does not cause shortening or lengthening of one side of the ladder tape when the slats are tilted to maximum tilt position.

20 Each end of the slats is provided with a centrally disposed pointed end projection which is adapted to extend into the associated V-shaped guide channel, as shown in Fig. 3. These end projections retain the slats against lateral displacement, permit their being readily tilted, and maintain the slats in vertical alignment during raising and lowering movements.

25 Raising and lowering of the slats is accomplished by means of a lift bar, generally indicated at 66, which is disposed below the lowermost slat of the blind. The projecting ends of the lift bar 66 are tapered similar to the projecting portions at the ends of the slats so as to fit the associated guide channel. The lift bar 66, at its projecting end, is provided with an inclined downwardly opening groove 70 which terminates at its uppermost end adjacent the upper surface of the bar and forms a passage-way for a flexible connection 71, in this instance, a flexible cable. This end of the cable 71 is anchored at the bottom of the tilt bar as by a screw 72. Where the cable passes around the upper end of the groove at the upper surface of the tilt bar, the cable is retained by means of a clip as shown at 73.

30 With the foregoing arrangement, although the end of the cable 71 is secured at the bottom of the lift bar, the pulling forces are in effect applied at the top of the bar so that the weight of the bar will tend to maintain the bar in vertical position. The cables at each end of the lift bar are carried through the guide channels and over the pulleys 30 where they are connected to the mechanism for raising and lowering of the slats, which is clearly disclosed in the aforesaid co-pending application.

35 Referring to Fig. 7, an alternative arrangement of releasable tilt bar construction is shown. Instead of utilizing a collar and set screw for securing the telescoping extension 31a in adjusted position, a spring 102 is disposed in the hollow bar 29a with one end abutting the associated end of the member 31a and its other end abutting a stop 103 which may be in the form of a rivet extending through the bar. In order to limit longitudinal movements of the member 31, this member is provided with a stop pin 104 which is disposed for movement longitudinally of a slot 105 provided in the wall of the bar 29a. With this arrangement, the removal of the tilt bar is facilitated, as it is only necessary to retract the member 31a against the pressure of the spring in order to withdraw the outer end of the member 31a from its pivotal support.

40 Figs. 8 and 9 disclose an alternative arrangement of ladder tape supporting brackets on the tilt bar. In this arrangement, the bracket is con-

structed from a flat plate 106 which is stamped or otherwise formed with struck up lateral portions 107 and 108 and an intermediate struck down portion 109. The lateral portions 107 and 108 extend over the top of the bar, whereas the intermediate portion 109 extends under the bar and securely holds the plate in position on the bar. With this construction, the plate projects on either side of the bar in a horizontal plane passing through the center line of the bar. At each end of the plate aligned struck up lugs 110 and 111 are provided which are adapted to receive thereover grommets 112 placed in the end margins of the ladder tape. The tape ends are held against removal from the lugs 110 and 111 by means of a clamp 113 which is arranged to extend over the extreme end portions of the ladder tapes and have its ends bent around and under the plate.

Since the material forming the brackets is of relatively small thickness and since the points of engagement of the ladder tapes with the ends of the brackets are disposed in the plane of the line of the tilting bar, there will be no appreciable shortening or lengthening of the ladder tape when the tilt bar is tilted.

It is, of course, to be understood that although I have described in detail several embodiments of my invention, the invention is not to be thus limited but only insofar as defined by the scope and spirit of the appended claims.

I claim:

1. A Venetian blind assembly comprising a tilt bar, a plurality of slats supported from the tilt bar, means for pivotally supporting the bar including a frusto-conical head rigidly secured to one end of said bar, a socket member forming part of said supporting means and having a frusto-conical interior wall frictionally embracing said frusto-conical head, said bar having telescoped portions, whereby the bar may be shortened to remove it from said means.

2. A Venetian blind assembly comprising an elongate bar having an end extension supported for axial movements, a spring normally maintaining said end in extended position, means pivotally supporting said bar at said extension, means pivotally supporting said bar at its other end including a frusto-conical head rigidly secured to said other end of said bar, a socket member forming part of said supporting means for said second end and having a frusto-conical interior wall frictionally embracing said frusto-conical head, said bar being removable from the supporting means when the extension is retracted against the pressure of said spring, and a plurality of slats supported from said bar.

3. In a Venetian blind, a tilt bar, a plurality of slats supported from said bar, said slats being tiltable in response to the tilting movements of said bar, and means for tilting said bar including a swingable lever having a connection with said bar including a frusto-conical head rigidly secured to one end of the bar and a frusto-conical socket operatively associated with said lever

and frictionally embracing said head, releasable means for readily affording disengagement of said head from said socket, and detent means for releasably retaining the bar in adjusted tilted position.

4. In a device of the character described, a vertically disposed plate, a tilt bar having one end pivoted in said plate, a plurality of slats supported from said bar tiltable in response to the tilting movements of said bar, a spring pressed member carried by said bar having an end movable over said plate, spaced dwell points on said plate for said end corresponding to positions of adjustment of said bar, an actuating lever pivoted on said plate for swinging movement, and a gear connection between said lever and said bar, whereby swinging movements of said lever are transmitted to said bar.

5. In a device of the character described, a plurality of slats, a ladder tape for supporting said slats, a bar disposed for tilting incident to variations of the angularity of the slats in cooperation with the ladder tape, a bracket carried by said bar having a projection thereon, a grommet in the upper end portion of the ladder tape, and means retaining the tape connected to said bracket with the grommet over said projection.

6. In a device of the character described, a plurality of slats, a ladder tape for supporting said slats, a bar disposed for tilting incident to variations of the angularity of the slats in cooperation with the ladder tape, a bracket carried by said bar including a pin, a metallic clip secured to the upper end of the ladder tape adapted to be disposed over said pin, and means removably retaining said clip on said pin.

7. In a Venetian blind assembly, a plurality of slats, a ladder tape for supporting said slats, a bar disposed for tilting incident to variations of the angularity of the slats in cooperation with the ladder tape, a pair of arms extending outwardly from said bar, one of said arms being fixed relative to the bar and the other supported for movements towards and away from the fixed arm, a pin secured at one end to one of said arms, means carried by the other of said arms for releasably connecting it to the free end of the pin, and means for supporting the ladder tape at its upper end from said pin, said tape end being removable from said pin when the arms are relatively moved to positions wherein the arm connected to the free end of the pin is disengaged.

8. In a Venetian blind, a plurality of slats, a ladder tape for supporting said slats including a main tape at each of the opposite sides of the slats, a rockable bar for tilting said slats, a pair of arms respectively projecting laterally from the opposite sides of said bar, pins at the outer ends of said arms, and loops on the ends of said main tapes through which said pins extend, the axes of said pins and said rock shaft being disposed in a single straight line parallel to the planes of the slats supported by said ladder tape.

FRED E. LAWSON.
